Primary Examiner—Paula A. Mortimer

(57) **CLAIM**

The ornamental design for a trigger pump package, as shown and described.

DESCRIPTION

FIG. 1 is an isometric view of my design for a trigger pump package,

FIG. 2 is a front view thereof;

FIG. 3 is a top view thereof;

FIG. 4 is a left-side view thereof;

FIG. 5 is a right-side view thereof;

FIG. 6 is a bottom view thereof;

FIG. 7 is a side elevational view thereof;

FIG. 8 is a second embodiment of an isometric view of my new design for a trigger pump package;

FIG. 9 is a front view thereof;

FIG. 10 is a top view thereof;

FIG. 11 is a left-side view thereof;

FIG. 12 is a right-side view thereof;

FIG. 13 is a bottom view; and,

FIG. 14 is a side elevational view thereof.
